UNITED STATES PATENT OFFICE.

CLAUDE HENNESSEE, OF MACON, GEORGIA.

DISTRIBUTING APPARATUS.

1,076,673.

Specification of Letters Patent. Patented Oct. 28, 1913.

Application filed July 23, 1913. Serial No. 780,837.

To all whom it may concern:

Be it known that I, CLAUDE HENNESSEE, a citizen of the United States, residing at Macon, in the county of Bibb and State of Georgia, have invented certain new and useful Improvements in Distributing Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in guano distributors and the object in view is to produce a simple and efficient device of this nature comprising essentially an oscillating receptacle which is actuated by suitable mechanism driven by pins projecting from a rotatable wheel, the receptacle having a spout which will spread the fertilizer broad-cast by its being suddenly swung back and forth as the apparatus moves over the field.

My invention comprises various details of construction and combinations and arrangements of parts which will be herein-after fully described, shown in the accompanying drawings and then specifically defined in the appended claims.

I illustrate my invention in the accompanying drawings, in which:—

Figure 1 is a side elevation of a guano distributor made in accordance with my invention, and Fig. 2 is a sectional view through the receptacle showing the parts in dotted lines.

Reference now being had to the details of the drawings by letter, A designates the beam of the apparatus having a knee or standard B to which a plow C is fastened, and D designates a wheel which is provided with an axle D' journaled in the downwardly extending portion E of said beam. Pins F project from the face of the wheel and are adapted to trip a pivotal lever H mounted upon the pin I carried by the handles K. A fertilizer receptacle N has a pintle O projecting from the bottom thereof centrally and forms an axial pivot which is journaled in suitable bearings O' in the plate O² upon said beam, said receptacle being adapted to be given a partial rotary movement back and forth in opposite di-

rections. A spout N' is fixed at one end to the lower portion of the receptacle and is adapted to communicate with the exit opening N² regulated by a slide N³ and which spout is adapted to swing back and forth with the receptacle as it is rocked axially.

A link P is connected at one end to an eye P' upon the receptacle and its other end is attached to the lever H through one of the apertures H' therein. A spring R is bent to form a coil R' and one arm of said spring is fastened to an eye S on the bottom of the receptacle, while the other end engages a pin T secured to the plate O².

The upper end of the lever H is provided with an aperture H² which, when the lever is tilted to register with an aperture K', is adapted to receive a pin to hold the lever out of operative position by a pin K² passing through said registering apertures.

The operation of my invention will be readily understood and is as follows:—When the apparatus is driven forward, causing the wheel to rotate, the pins F coming successively in contact with the lower end of the lever H will cause the same to tilt and in the tilting of the lever the link P will cause the receptacle to make a partial rotary movement. This axial movement, which is imparted to the receptacle, will put the spring R under tension so that the moment the lower end of the lever H passes by a pin F and is free therefrom, said spring will return the receptacle to its normal position, the return movement being stopped by the pin S' coming in contact with the pin T. The sudden stoppage of the rocking or axial movement to said receptacle will cause a jar which will tend to cause the fertilizer to be loosened and thrown out through the spout N'. It will be noted that, as the receptacle makes its axial movements in opposite directions, the spout swinging therewith will have a tendency to scatter the fertilizer broad-cast, first upon one side and then the other of the apparatus.

When it is desired to hold the parts from operation, the lever may be held back so that its lower end will be out of the path of the pins F, the wheel then being free to turn without operating the receptacle.

What I claim to be new is:—

1. A fertilizer distributor comprising a beam with handles thereto and a wheel jour-

naled in suitable bearings in said beam, an axially oscillating fertilizer receptacle mounted upon said beam, a spout fixed to the receptacle, a lever pivotally mounted upon the handle, projections upon the wheel adapted to tilt said lever as the wheel rotates, means intermediate the lever and receptacle for imparting a partial axial oscillatory movement to the receptacle in one direction, and a spring adapted to return the receptacle to its normal position, as set forth.

2. A fertilizer distributor comprising a beam with handles thereto and a wheel journaled in suitable bearings in said beam, an axially oscillating fertilizer receptacle mounted upon said beam, a spout fixed to the receptacle, a lever pivotally mounted upon the handle, projections upon the wheel adapted to tilt said lever as the wheel rotates, a link pivotally connected at one end to said lever and its other end connected to the receptacle, a spring connected to one end of the receptacle and its other end engaging a projection on the beam and adapted to be put under tension as the receptacle is oscillated in one direction, as set forth.

3. A fertilizer distributor comprising a beam with handles thereto and a wheel journaled in suitable bearings in said beam, an axially oscillating fertilizer receptacle mounted upon said beam, a spout fixed to the receptacle, a lever pivotally mounted upon the handle, projections upon the wheel adapted to tilt said lever as the wheel oscillates, a link pivotally connected at one end to said lever and its other end connected to the receptacle, a spring connected to one end of the receptacle and its other end engaging a projection on the beam and adapted to be put under tension as the receptacle is oscillated in one direction, a pin projecting from said receptacle and adapted to contact with said projection to limit the oscillatory movement of said receptacle as it returns to its normal position, as set forth.

In testimony whereof I have hereunto affixed my signature in presence of two witnesses.

CLAUDE HENNESSEE.
